UNITED STATES PATENT OFFICE.

WILLIAM N. PARKES, OF BROOKLYN, NEW YORK.

SEWING-MACHINE.

1,207,437.

Specification of Letters Patent. Patented Dec. 5, 1916.

Application filed August 7, 1914. Serial No. 855,598.

To all whom it may concern:

Be it known that I, WILLIAM N. PARKES, a citizen of the United States, residing in the borough of Brooklyn, in the county of Kings 5 and State of New York, have invented new and useful Improvements in Sewing-Machines, of which the following is a specification.

This invention relates to the class of sewing machines in which there is mechanism for producing a relative lateral movement between one or more needles and the work. In these machines this relative lateral movement may be to and fro, or it may be a lateral movement in one direction during the making of a plurality of stitches, and then a lateral movement in an opposite direction during the making of one or more stitches.

The preferred form of my invention herein, is described and illustrated adapted for use in a well known machine of the class mentioned wherein a reciprocating needle is moved laterally to and fro, and in which the feeding mechanism is of the four motion kind, but, it is desired that it be understood that the use of the invention is not limited to this particular type of machine. And it is also desired that it be understood that while the main use for the invention is in the class of machines mentioned, it is not limited to this class, for it, or a part of it, may be used in machines in which there is no relative lateral movement between the needle and the work.

As is well known, in the operation of lock stitch sewing machines, a thread carrying needle passes a loop of needle thread through the work and presents it to a hook, which latter seizes it and passes it around a bobbin case carrying a bobbin of thread, the loop of needle thread being thereby caught around the portion of the bobbin thread which runs from the bobbin to the work, then the take-up draws up the loop until the bobbin thread and the needle thread at the point where they are looped together are drawn and anchored into the work where the needle previously penetrated it, and a stitch is said to have been made, then after the feed has completed the movement of the work for the location of a succeeding stitch, the needle is again passed through the work and another stitch is made as before, and so on. The portions of the needle thread which runs

from one to another of these stitches are 55 called herein links of needle thread, and the portions of the bobbin thread which runs from one to another of these stitches are called links of bobbin thread.

The invention herein disclosed relates to a 60 sewing machine comprising a laterally vibrating needle, an auxiliary thread carrying looper, and improved means for operating it to loop its thread around the links of needle thread; means coöperating with the auxiliary looper to draw a portion of the links of needle thread around the looper thread so that said portions and the looper thread abuts the edge of the fabric; improved 65 means for hemming the work in combination 70 with the working of the auxiliary looper; means intermediate the needle and the raw edge of the material whereby the edge of the material is covered so that the ends of its threads are bent and bound down under the 75 links of needle thread and under the auxiliary thread; a feeding mechanism the feed dog of which extends into the needle slot, and between the reciprocating paths of the 80 needle, a special form of presser foot adapted for use in combination with the feed dog and the auxiliary looper, and other improvements which will be described in the specification and specifically set forth in the 85 claims.

Referring to the drawings, Figure 1 is a front elevation, and Fig. 2 a rear elevation of a machine in which the invention is incorporated. Fig. 3 is an enlarged front end view with the face plate removed. Fig. 4 is a top plan view of one of the needle plates, Fig. 5 is a top plan view of one of the feed dogs, and Fig. 6 is a top plan, and 7 a side elevation of one of the presser feet. Fig. 8 is a top view showing 90 the hook mechanism, the special feed dog, and the relative position of the said feed dog to the hook mechanism, and Fig. 9 is a sectional view of the presser foot bar showing its construction and the parts carried by it. Fig. 10 is a top plan view of the special 95 presser foot, the special guide, and the auxiliary looper, and the hemmer in position. Fig. 11 illustrates the special feed dog in one of its positions, and Fig. 12 in another of its 100 positions. Figs. 13 and 14 illustrate the special foot and Figs. 15 and 15^a details of the special guide. Fig. 16 is a diagrammatic

view illustrating how the auxiliary thread is looped around the links of needle thread, and Fig. 17 is a similar illustration showing how the stitches are drawn to the edge of the fabric, also illustrating in dotted lines how the links of bobbin thread run from one to another of the stitches on the under side of the fabric. Fig. 18 is an end view of the base of the machine illustrating how work 10 may be guided automatically under the presser foot, and Fig. 19 is a top plan view illustrating the same. Fig. 20 is a bottom plan view of the special presser foot and Fig. 21 is a modification of the special feed dog 15 and needle plate. Fig. 22 is a diagrammatic view illustrating the stitches when two needles are used in combination with the auxiliary looper thread, and Fig. 23 is a diagrammatic view illustrating how the auxiliary looper thread may be drawn so as to locate it along the edge of the stitched path. Fig. 24 illustrates how two needles may be carried by the needle bar.

In the drawing 1 is the arm, 2 the base, 3 the face plate, and 4 the hand wheel of the machine. In the arm is suitably journaled a driving shaft 5, which carries a belt pulley 6, on which is mounted a belt 7 that runs over a pulley 8 secured to a hook shaft 30 9 as shown in dotted lines in Figs. 1 and 3. The pulley 8 is one half the size of the pulley 6, therefore it will be understood that the hook driving shaft revolves twice to each revolution of the driving shaft 5.

35 To the forward end of the hook driving shaft is secured a beveled gear 10, that engages a beveled gear 11, the latter being secured to a short shaft 12 which is mounted in suitable bearings (see Fig. 3). The beveled gears are of equal size therefore it will be understood that the hook driving shaft and the hook shaft revolve in unison. To the rear end of the hook shaft is secured a hook 13, provided with a bobbin case 14, 40 which carries a bobbin of thread in a usual manner not shown. A projection 15 extending from the bobbin case holder and a stop finger 16 serve in a usual manner to restrain the bobbin case from rotating (Figs. 45 50 3 and 8).

On a bearing 17, (see Fig. 3) is pivoted a needle bar frame 18 in which is mounted to reciprocate a needle bar 19, which carries a needle 20. The needle bar is reciprocated by means of a crank pin 21 carried by a part 22, which latter is suitably secured to the forward end of the driving shaft 5. On the crank pin is pivoted the upper end of a link 23 which at its lower end is suitably connected, by means not shown, to the upper end of the needle bar. The connection between the link 23 and the needle bar is of a usual character which permits of the needle bar being moved laterally.

60 65 On the driving shaft 5 is secured a spiral

gear 24, (Fig. 1) which engages a spiral gear 25, secured to a short transverse shaft 26, suitably mounted in the arm of the machine. On the shaft 26, within the arm, is secured an eccentric (not shown) on which in a suitable manner (not shown) is mounted one end of a pitman 27. The other end of the pitman is pivoted on a bearing 28, carried by the lower end of the needle bar frame 18. The eccentric is mounted so it 70 75 may be moved toward or from the center of the shaft 26, and suitable means (not shown) intermediate the eccentric and a thumb nut 29 serves to adjust the eccentric. This means is constructed so the eccentric 80 may be adjusted outwardly from a position where its axis is concentric with the axis of the shaft 26, or vice versa, so it will be understood that usual means are in the machine for adjusting the means for moving 85 the needle laterally out of action when the needle will reciprocate vertically only as in a plain stitch machine.

The gear 25 is twice the size of the gear 24, therefore it will be understood that the 90 eccentric which operates the pitman 27 revolves once to two revolutions of the driving shaft of the machine. When it is desired to have the needle moved laterally the eccentric, by means of the thumb nut 29, is adjusted to give the desired extent of movement to the pitman 27. As is usual in these machines during one half of a turn of the eccentric, and just as it has moved the needle bar substantially to one of its lateral positions, the needle enters the work, loop engagement takes place, and a stitch is made, then when the eccentric is in the same position in the other half of its rotary movement the needle again enters the work in its other 100 lateral position and another stitch is made and so on. Intermediate the entering of the needle in the work, the feeding mechanism moves the work to the desired position for the location of the succeeding stitch.

105 On the rear end of the shaft 26 is secured by means of screws 30 a cap 31, in the outer wall of which is formed a way 32 that extends from over the center 33 of the cap to its edge. The axis of the cap is concentric 110 with the axis of the shaft. This cap serves the function of a collar for the shaft to retain it in its position longitudinally, and also as a means for transmitting movement to a pitman 34, the end 35 of which is secured by means of a thumb nut 36, in the way 32. It will be observed that when the end 35 of the pitman is adjusted over the center 33 of the cap, no movement is transmitted to the pitman, and consequently no 115 movement is transmitted to the mechanism operated by the pitman.

120 125 The forward end 37 of the pitman is suitably pivoted on a ball end 38, of an arm 39, which latter is secured at its other end, by 130

means of a screw 40, in a looper rod 41. In suitable bearings in the forward end of the arm of the machine is mounted a tubular presser bar 42. In the upper end of the bar 5 is a bore 43, that extends to 44, and from this point to the lower end of the bar is a bore 45 that is smaller than the bore 44, as shown in Fig. 9. Abutting the end 44 of the bore 43 is a bushing 46, in which the upper end 10 of the rod 41, is journaled, and in the lower end of the bore 45 is a bushing 47 in which is journaled the lower end of said rod.

Through a slot 48 in one side of the presser bar, passes the arm 39, which is flattened on its upper and lower sides at the point where it is in the slot so that it just fits the slot and thereby the rod is held from longitudinal movement. The slot is of sufficient length to allow the arm 39 to be moved 20 laterally the desired distance. To the outside of the presser bar is clamped, by means of a screw 49, an arm 49. This arm extends into a slot 49" in a part 49''' and thereby prevents the bar from turning, and at the 25 same time permits it to be lifted and lowered in the usual manner.

Loosely mounted on the outside of the bar is a sleeve 50, provided with an arm 51. An end 52 of the sleeve abuts the arm 49, and a 30 usual pivoted presser foot lifter lever 53 (see Fig. 3) is located under the arm 51, and serves as means for manually lifting the bar. In the bore 43 of the bar is located a presser bar spring 54, which at its lower end 35 impinges against the bushing 46, and at its upper end against an adjustable bearing 55, which is located in a threaded bore in the arm of the machine.

In the operation of lifting the presser foot 40 the lever 53 is turned on its pivot upwardly, when the usual cam portion 53' of the lever engages the arm 51, and the sleeve is thereby lifted upwardly, and through its contact with the arm 49 the presser bar and mechanism carried by it are lifted upwardly 45 against the action of the spring 54 as will be understood from Figs. 3 and 9. And of course a reverse movement of the lever 53 permits the spring to press the presser bar 50 downwardly, until the presser foot, which will presently be described, engages the work. The extent of the pressure of the foot on the work is regulated by the adjustable bearing 55.

To the lower end of the presser bar is secured by means of clamping screw 56 a presser foot carrier 57, to which is secured by means of screw 58, the shank 59 of the special presser foot 60, provided with an 60 open end needle slot 61, nearly across which projects a tongue 61'. In a groove formed in the upper side of the presser foot, is adjustably secured by means of a screw 62, an auxiliary looper thread guide 63, provided 65 with upwardly extending end 64, in which

is formed a thread eye 65. It will be observed that this construction permits of the lateral adjustment of the guide, and also permits of its being reversed so that the end 64 may be located on the opposite side 70 of the presser foot to that in which it is shown in Fig. 13.

To the lower end of the looper rod 41, is secured by means of clamping screw 66 (see Fig. 10) a looper carrier 67. In a way 68, 75 is adjustably secured by means of a screw 69, a shank 70 of an auxiliary looper 71, the shank of the looper being provided with a slot 72 through which passes the screw 69 into a seat in the carrier. The auxiliary 80 looper is provided with a nose 73, through which passes a thread eye 74. The slot 72, it will be noticed permits of the adjustment of the looper so the path of action of its nose may be changed relative to the field of 85 action of the needle.

In the shank of the presser foot is a way 75, in which is secured by means of screw 76, an arm 77, which carries a scroll hemmer 78. In the operation of the machine, the work enters the hemmer under the leaf 79, and is folded under. It will be observed that as this hemmer is carried by the presser foot, when the foot is lifted the hemmer is lifted, and there is then a free passage under 95 the foot from any direction.

In the preferred form of my invention a usual form of feed dog carrier 79', carries a feed dog 80, which has upwardly extending toothed work engaging portions 81 and 82, 100 between which there is a thread passage space 83. A needle plate 84 is provided with a feed dog slot 85, a needle slot 86, and a feed dog slot 87, one end of slot 87 opens 105 into the needle slot as shown in Figs. 11 and 12. This feed dog, through the movements of the carrier 79', and the mechanism which operates the carrier, (not shown) is given the usual well known four motion feeding movement. Under this movement the work 110 engaging portions 81 and 82 of the feed dog are moved upwardly through the slots 85 and 87 into engagement with the work, then it is moved forward and this moves the work one step in its feeding movement, then 115 the dog is moved downwardly out of engagement with the work, then backward and upwardly again into engagement with the work and so on. In the machine in which I have incorporated my invention the feed- 120 ing mechanism has the usual means for increasing or decreasing the extent of the forward and backward movement of the feed dog, and thereby increasing or decreasing the length of the stitch as it is usually 125 called, but, the distance between the stitches as the stitching is herein defined.

A guide 88 is secured by means of a screw 89 to the cloth plate of the machine. This guide is provided with a work abutting face 130

indicated by reference characters 90 and 91, thread passage slot 92, undercut portion 93, (in dotted lines Fig. 15) needle separating tongue 94 and auxiliary thread abutting 5 part 95, and needle recess 95'.

In Figs. 4, 5, 6 and 7 are shown a feed dog, needle plate, and presser foot for general use in connection with my invention. 10 96 is the general presser foot in which is formed a needle passage 97, adjacent to the passage at each end are slots 98 and 99 that incline downwardly toward the needle slot, and intermediate these slots are auxiliary thread abutting corners 100 and 101, the 15 back of the needle passage is 102 and the front 103. Central of the movements of the needle is a tube 104 which extends into the needle passage, the bore of the tube being 105. In a way in the top of the presser foot 20 is adjustably secured by a screw 106 an auxiliary thread guide 107 having an upturned end 108, provided with a thread eye 109. The presser foot is pivoted at 110 to an extending end 111, of a presser bar shank 25 112, which latter is provided with a slot 113, and is adapted to be secured to the presser foot carrier 57 in the same manner as is the special preferred form of presser foot that has been described. In the use of this general 30 presser foot the feed dog which is generally designated by 114, and the needle plate 115, are substituted for the needle plate 84 and the feed dog 80 previously described.

35 In the operation of the machine, if it is desired to bind the raw edge of a piece of fabric, the feed dog 80, needle plate 84, guide 88, and special presser foot 60 are secured in place in the machine as illustrated 40 in Figs. 1, 3 and 10, but with the hemmer omitted. The extent of the lateral movement of the needle is adjusted so that it moves the needle laterally a sufficient extent to cross the toothed portion 81 of the feed dog, and alternately reciprocated on each 45 side of the same. The extent of the steps of the feeding movement desired is adjusted by a thumb nut 114, which in a usual manner (not shown) connects with means for 50 regulating the feeding movement of the feed dog, as before noted.

55 In threading the machine the needle thread 115 is passed from the supply through an eye 116 in a pin 117 projecting upwardly from the arm of the machine. From thence it is passed through a guide 118, over a guide 119, then under the tension 60 120, from there up through the take-up eye 121, in the end of a take-up 122, and from 65 there down to the needle as will be understood from Fig. 1. The auxiliary thread 123 passes from the supply to an eye 124 in the face plate 3, then back and under a pin 125, thence between tension disks 126 (only 70 one of which is shown) and from there back

and under a pin 127, then over a loop 128 of the extending end of a usual constructed spring (not shown). From this spring the auxiliary thread runs to the eye 65 of the thread guide 63, and from there it passes 75 through the eye 74 of the nose 73 of the auxiliary looper.

The auxiliary looper 71 is moved laterally in the same direction the needle is moved laterally, but always a greater extent than the needle. For example when the needle is moved to the right, the looper is moved, so its nose 73 is to the right of the needle as it, the needle, descends to the work, and the nose extends sufficiently back of the 80 needle to carry the auxiliary thread running from the previous stitch back of the needle, and when the needle is moved to the left the said looper is moved to the left so its nose is to the left relative to the needle in 85 the same manner. The result is the auxiliary thread runs back under each link of needle thread and forward over the top of the same as will be understood from diagrammatic Fig. 16.

90 It will be noticed that the thread eye 64 is a considerable distance to the left of the reciprocating path of the needle. This serves to cause the looper thread to be slack when the looper moves to its position 95 to the left, and to be taut and to draw the supply of looper thread when it moves to the right. This movement to the right is against the action of the spring 128, and this together with the location of the thread eye 64 and the proper timing of the looper so that the take-up begins to give thread just previous to the auxiliary thread commencing to draw it, the needle thread to one side, causes the needle thread to be looped 100 around the looper thread at the edge of the stitching as illustrated in diagrammatic Fig. 17. When this stitching is done along the edge of a piece of fabric so that the needle in one of its reciprocating movements 105 passes to loop engagement outside of said edge the needle thread is drawn around the looper thread as illustrated in Fig. 17, and when so drawn the looper thread abuts the 110 raw edge of the fabric and thereby gives a 115 smooth and very desirable finish to the same. The bobbin thread is an element in performing this function, as the usual tension on it draws on the needle thread and thereby assists in drawing the looper thread to the desired position.

In finishing the raw edge of a piece of material the said raw edge is inserted under the presser foot abutting the face of the guide 88. The ragged edge or extending 120 ends of the cross threads of the fabric, should there be any, are drawn against the face of the guide taut enough to bend them. This is accomplished by the action of the auxiliary looper, which tends to pull the 125 130

fabric toward the guide by reason of its thread always being taut and pulling the supply of looper thread when moving in that direction, and as a further means for assisting in accomplishing this function the face of the guide is under cut as best indicated in Fig. 12.

The bent ends of the thread, as the feed of the work progresses, are held down by the presser foot, and are held against the edge of the fabric by the separator tongue 94, and, the needle thread from the stitches made when the needle enters the needle recess 95 together with the looper thread bind these ends of the fabric thread to the edge of the fabric, thereby giving a very firm and desirable finish to said edge.

When it is desirable to do hemming, a hemmer may be attached to the presser foot as shown in Fig. 10, and the guide may also be used for the edge of the work to abut against, thereby assisting in guiding it and holding it from having a tendency to be pulled to the right from the action of the auxiliary looper thread in setting the stitch, and also serving as a means for assisting in the setting of the stitch with the auxiliary thread along the edge of the hem. When a hemmer is used the auxiliary thread abuts along the outer edge of the hem, and thereby makes a very desirable finish. This auxiliary thread may be any kind of thread or cord in any color, which further adds variety and scope to the finished effect.

The function of the abutting part 95 of the guide 88 is to serve as an abutment for the auxiliary thread to abut against, and thereby prevent it from pinching the needle thread when the stitch is being set. This will be understood by referring to Fig. 15, and noting that when the stitch is being set the auxiliary thread is pulled to the right so it abuts the abutment 95, and thereby permits the needle thread to pass back of the looper thread without being pinched between it and the guide.

When it is desired to hem the edge of a piece of fabric, and at the same time sew a piece of lace or other material along the edge, the guide 88 is removed, the part 63 may be reversed so it is in an opposite position as shown in dotted lines in Fig. 13. This puts the finish along the edge of the left of the stitched path where it is very desirable in this kind of work. Now the lace is guided along the edge of the presser foot at the right, and as the needle reciprocates just outside of this edge the lace is connected to the edge of the hem by the stitches so that it substantially abuts said edge.

When it is desired to do general plain or ornamental stitching, or broad hemming, or hemming with the hemmer attached to the bed of the machine, the feed dog, needle

plate, and presser foot, illustrated in Figs. 4, 5 and 6 are used. In the presser foot shown in Fig. 6, abutting parts 100 and 101 together with recesses 98 and 99 serve to prevent the looper thread from pinching the needle thread, in substantially the same manner as has been described in connection with the guide 88. The feed dog work engaging part 81 is moved to the position shown in Fig. 12 in moving the work forward, in which position it will be observed that the toothed portion is past the reciprocating path of the needle. Of course the position of this feed dog relative to the reciprocating path of the needle, in the finishing of a feeding movement, is changed when the extent of feeding movement of the dog is changed. This construction and location of the feed dog is very advantageous in various kinds of work. Take for example the edging of a square piece of material, such as a handkerchief, or napkin, when the needle enters the work the feed dog is substantially flush with the top surface of the needle plate 84, consequently the extreme corner of the work is supported and therefore is not pushed down into the needle slot by the thrust of the needle. The tongue 61' serves for the extreme rear end of the part 81 of the feed dog to press the work against when feeding it forward, thus it will be understood that the construction of the feed dog so it operates in the same manner described serves as a means for the feed dog engaging the work at the extreme edge of the corner just where it is desirable to commence the stitching. This is advantageous in any kind of work where it is desirable to commence the stitching at the extreme edge or corner.

When the general presser foot 96 is used, a filling cord or material may be run from the supply to the eye 129, from thence to guide 130, and then through the eye 105 in the tube 104 which guides it under the lateral path of the needle. Of course a tube may be inserted, or any other suitable means may be provided to run a filling material under the lateral path of the needle, when the special presser foot, or any other presser foot is being used. If it is desired to use two needles and to produce the stitching illustrated in Figs. 22 and 23 the two needles may be carried by the needle bar in any usual manner for example in the manner illustrated in Fig. 24. These needles are located abreast, at right angles to the direction of the feed. In said Figs. 22 and 23 the needle 131 represents the additional needle, 132 its thread, and 115 the needle thread of needle 20. In using these two needles the usual adjustment is made by means of thumb nut 29, to discontinue the lateral movement of the needle bar, so that both needles reciprocate vertically without lateral motion. The two needles are sepa-

rated a sufficient extent so that one reciprocates on one side of the portion 81 of the feed dog, and the tongue 61', and the other needle on the other side of the said feed 5 dog portion and tongue.

In the operation of the machine with two needles in it, the auxiliary looper is operated in the same manner as has been described in connection with the use of one needle.

- 10 The needles are passed through the work, the hook seizes the loop of the needle threads of both needles and passes them around the single bobbin in the usual way. The auxiliary looper thread, to make the stitches illustrated in Fig. 23, is threaded through the eye 65 of the thread guide 63. This causes said thread to be taut when the auxiliary looper moves to the right at which time the supply of auxiliary looper thread is drawn, 15 and to be slack when the looper is moved to the left when no auxiliary looper thread is drawn. From this action the needle thread from the needle at the left and also the auxiliary looper thread are drawn to the right, and to the edge of the fabric, or 20 stitched path as illustrated in Fig. 23. In making these stitches the bobbin thread will connect the stitches on the under side of the fabric as illustrated in dotted lines in 25 Fig. 23.

In the use of the preferred form of presser foot 30 the tongue 61' serves, in addition to its other functions, to take the strain of the lateral stitches, thereby permitting of a 35 suitable tension being on the thread to set the stitches without puckering the work.

In the preferred form of my invention, in which form the auxiliary looper draws its thread and the needle thread with which 40 it concatenates to the edge of the stitched path, or to the edge of the fabric when it is desired to cover such edge, the looper is constructed and operated so it finishes its stitch setting movement after the take-up has finished its stitch setting movement as before noted. The finishing of the stitch setting movement of the take-up is at the time when the take-up has reached its highest position, which is substantially the position shown in 45 dotted outline in Fig. 3, and the finishing of the stitch setting movement of the auxiliary looper is, when the stitch is being set on the right of the stitched path for example, substantially in the position shown in 50 dotted outline in Fig. 11. By this construction and operation the auxiliary thread and the links of needle thread are firmly looped and set abutting the edge of the fabric, or 55 when stitching is on the interior of the work, along the edge of the stitched path.

The work of the character done by the invention herein illustrated, is very advantageous for use in finishing the edge or edges 60 of strips of material. To the end that this 65 may be done at a minimum cost, I have

provided means for guiding such strips of work to the feeding mechanism, so that it will run through automatically without any assistance from the operator.

The means for guiding the strips of work 70 so the machine will finish an edge of the same automatically comprises the following: To the top of the bed 2 of the machine (see Figs. 18 and 19), is secured by means of screws 133, a bracket which is generally 75 designated 134. This bracket has upwardly extending arms 135, in which is suitably located a spindle 136, which carries a roll of material 137. The bracket is provided with horizontal arms 138 in which there is suitably located to revolve a roller 139.

In the operation of the machine, to finish the edge of strips of material, the strip runs from the supply carried by the spindle 136, under the roller 139, and thence under the 80 presser foot, as shown in Figs. 18 and 19. The spindle and roller turn very freely on their bearings so it will be understood that the feed dog very readily carries the work along automatically while the machine is 85 finishing the edge. In connection with doing this work automatically it is noted that while the mechanism is own adapted for stitching only one edge of the material, it is obvious that by duplicating the means 90 shown a plurality of edges may be simultaneously stitched.

It is noted that with my invention as herein illustrated various work, other than the kind herein mentioned may be done, and also other functions may be performed. It is also noted that applicant does not want to be limited to the specific means, or construction, herein shown, as these may be 100 changed in various ways without departing from the spirit of the invention.

It is further noted that certain parts of the invention are not essential to the performance of the functions of the invention. For example, the guide 88 is not essential 105 to the weaving of the auxiliary thread with the needle thread along the edge of the work. The guide however serves to assist in guiding the work so that the stitching will be uniformly along the edge, and positioned so that the auxiliary thread will be 110 more certainly located along the edge.

Having now described my invention, what I claim is:—

1. In a sewing machine, a vertically reciprocating and laterally vibrating needle, a needle plate provided with a needle slot, said needle plate provided with a feed dog slot which extends into said needle slot and a feed dog acting in said feed dog slot.

2. In a sewing machine, a vertically reciprocating and laterally vibrating needle, a needle plate provided with a needle slot, said needle plate provided with a feed dog slot which extends in the direction of the 115 120 125 130 135

- feed of the work and opens into the needle slot, and a feed dog operating in said feed slot.
3. In a sewing machine, a vertically reciprocating and laterally vibrating needle, a feeding mechanism provided with a work engaging part which operates between the reciprocating paths of the needle, and a guide for the work which guides it so that 10 the needle reciprocates in one of its reciprocating paths outside the edge of the work.
4. In a sewing machine, a vertically reciprocating and laterally vibrating needle, a needle plate provided with a needle slot, a feeding mechanism comprising a feed dog, 15 said feed dog comprising two work engaging parts, one of said parts located to operate in the rear of the needle, the other of said parts located to operate in the front 20 of the needle and between the reciprocating paths of the same, and a guide against which the edge of the work abuts.
5. In a sewing machine, a vertically reciprocating and laterally vibrating needle, a feeding mechanism comprising a feed dog 25 which operates between the reciprocating paths of the needle, a guide for the work, a presser foot provided with a needle slot having an open end, said guide provided 30 with a slot which is coincident with the open end of said needle slot.
6. In a sewing machine, a reciprocating needle, a feeding mechanism, means for producing a relative lateral movement between 35 the needle and the feeding mechanism so the needle passes through the edge of the work in making one or more stitches, and outside of the edge of the work in making one or more stitches, a guide for the work 40 constructed of a single piece, said guide provided with a needle recess, and a part that is integral with the same that extends between the said needle recess and the work.
7. In a sewing machine, a vertically reciprocating and laterally vibrating needle, a guide against which the edge of the work abuts, said guide provided with a needle recess, a part of the wall of said recess constructed to extend between the needle and 50 the work and in line with the face of the guide, and an opening between said recess and the work.
8. In a sewing machine, a vertically reciprocating and laterally vibrating needle, an auxiliary thread carrying looper adapted to 55 loop its thread around links of the needle thread, an abutment against which said looper thread is drawn in setting the stitch, and said abutment constructed and located in position to prevent the looper thread from binding the needle thread.
9. In a sewing machine, a vertically reciprocating and laterally vibrating needle, an auxiliary thread carrying looper adapted to 60 65 loop its thread around links of the needle
- thread, a spring against which said looper thread acts when the stitch is being set, an abutment against which the looper thread abuts during the action of said spring, and said abutment constructed and located in position to prevent the looper thread from binding the needle thread. 70
10. In a sewing machine, a vertically reciprocating and laterally vibrating needle, an auxiliary thread carrying looper adapted to 75 loop its thread around links of the needle thread, a guide for the work, and an abutment formed on said guide against which the looper thread draws in setting the stitch. 80
11. In a sewing machine, a vertically reciprocating and laterally vibrating needle, a guide for the edge of the work, said guide provided with a needle recess, a needle separating tongue which separates the needle 85 recess from the face of the guide, and an auxiliary thread carrying looper.
12. In a sewing machine, a vertically reciprocating and laterally vibrating needle, an auxiliary thread carrying looper, a guide 90 for the edge of the work, said guide provided with a needle recess, a separating tongue which separates the recess from the face of the guide, the guide provided with a thread passage slot, and an auxiliary 95 thread abutting projection.
13. In a sewing machine, a vertically reciprocating and laterally vibrating needle, an auxiliary thread carrying looper, a guide 100 for the edge of the work to abut, said guide provided with a needle recess located inside the face of the guide, a tongue projecting between the needle recess and the face of the guide, the face of the guide comprising two parts one part located in the rear of the reciprocating path of the needle, and the other part in the front of said path, and an undercut in the part of the guide in front of said reciprocating path of the needle. 105
14. In a sewing machine, a vertically reciprocating and laterally vibrating needle, a presser bar, said presser bar provided with a bore, an auxiliary looper rod mounted in said bore, an opening in the wall of said presser bar, and an arm secured to said rod 110 115 extending through said opening, an auxiliary thread carrying looper carried by the lower end of said rod, and means for oscillating the said arm.
15. In a sewing machine, a vertically reciprocating needle adapted to be vibrated laterally, means for vibrating said needle laterally comprising a transverse shaft, means whereby said transverse shaft is rotated in one direction only when the machine 125 is operating, a cap on the rear end of said shaft, an auxiliary thread carrying looper, and means intermediate said cap and said looper whereby the looper is operated from the movement of the cap. 120 130

16. In a sewing machine, a vertically reciprocating needle adapted to be moved laterally, a presser bar, said presser bar provided with a bore that extends longitudinally through the same, an abutment in said bore, a presser bar spring in the upper part of said bore that impinges at its lower end against said abutment and at its upper end against an adjustable part, an auxiliary looper rod located in the other part of said bore, an auxiliary looper carried by said rod, means for moving the aforesaid needle laterally, and a connection between said means and the looper rod whereby the looper rod is oscillated from the movement of said means.

17. In a sewing machine, a vertically reciprocating needle, means for moving said needle laterally to and fro, an auxiliary thread carrying looper, means for moving said thread carrying looper laterally to and fro in unison with the lateral movements of the needle and a greater extent than the needle moves laterally, a guide against which the edge of the work abuts, a needle passage in said guide, and a tongue which extends between the needle passage and the work.

18. In a sewing machine, a vertically reciprocating and laterally vibrating needle, an auxiliary thread carrying looper adapted to loop its thread around links of the needle thread, a presser foot, a guide for said auxiliary thread carried by said presser foot, said guide provided with a thread eye, means for adjusting said guide laterally, and means for reversing the position of said guide so its thread eye may be on either side of the field of action of the needle.

19. In a sewing machine, a vertically reciprocating and laterally vibrating needle, an auxiliary thread carrying looper adapted to loop its thread around links of the needle

thread, a take up spring in engagement with said auxiliary thread, and means for guiding the work so that the needle in one of its reciprocating positions reciprocates outside the edge of the work.

20. In a sewing machine, a vertically reciprocating and laterally vibrating needle, a presser bar, an auxiliary thread carrying looper carried by said presser bar, a presser foot carried by said presser bar, a hemmer carried by said presser foot, and a guide for the work the face of which abuts said hemmer.

21. In combination in a sewing machine, a vertically reciprocating and laterally vibrating needle, mechanism for feeding the work, an auxiliary thread carrying looper, means for operating said looper to loop its thread around links of the needle thread, a guide against which the edge of the work abuts, and means for causing the auxiliary looper to draw its thread along the edge of the work between the guide and the work.

22. In combination in a sewing machine, a vertically reciprocating and laterally vibrating needle, a feeding mechanism, an auxiliary thread carrying looper, means for operating said looper to loop its thread around links of the needle thread, a guide against which the edge of the work abuts, means for causing the auxiliary looper to draw its thread along the edge of the work between the guide and the work, and a roller for carrying the work and from which the feeding mechanism automatically draws the same.

In testimony whereof I have signed my name in the presence of two subscribing witnesses.

WILLIAM N. PARKES. [L. S.]
